UNITED STATES PATENT OFFICE.

SIMON P. DILLON, OF DORCHESTER, MASSACHUSETTS.

ENVELOPE.

Application filed April 30, 1919, Serial No. 293,596. Renewed July 28, 1922. Serial No. 578,269.

To all whom it may concern:

Be it known that I, SIMON P. DILLON, a citizen of the United States, residing at Dorchester, in the county of Suffolk and State of Massachusetts, have invented a new and useful Improvement in Envelopes, of which the following is a specification, reference being had therein to the accompanying drawings.

10 My invention relates to envelopes and more particularly to an envelope having provision for carrying a card or slip on its outside surface.

At the present time, it is customary in postoffices, when a return receipt for a registered letter is demanded by the sender, to prepare at the mailing point a return receipt card which is then attached to the letter by a rubber band or metal clip or other similar device. It frequently happens, however, that in the various handlings to which the letter is subjected before it reaches its destination that the card becomes separated from the letter and the letter is delivered without securing a return receipt. The failure of the postoffice to return to the sender of the letter the return receipt then leads to a complaint on his part and a request for the receipt. This in turn necessitates an examination of the records of the registry division of the post office and the preparation of a new card which is forwarded for the signature of the addressee of the registered letter. The complaints originating from this cause alone require the services of a number of clerks in every large postoffice merely for investigation of the cases. Furthermore, the number of metal clips or other holding devices used in postoffices throughout the country costs in the aggregate a considerable sum every year.

45 The main object of my invention is to provide an envelope for use primarily for registered mail having a pocket formed on the outside to receive and hold securely the return or other card.

50 A further object is the provision of such means of the above character that the envelope may be formed from one suitable blank.

55 Another object is to provide an envelope the use of which will render metal clips or other fastening devices unnecessary and thereby obviate this expense.

Other objects of the invention will be

more specifically set forth and explained hereinafter.

In the accompanying drawings which illustrate the preferred embodiment of my invention, Figure 1 is a plan view of a blank from which an envelope may be made in accordance with my invention; Fig. 2 is a plan view of the reverse side of an envelope formed from the blank shown in Fig. 1, 60 with the flap designed to form the return card pocket turned outwardly; Fig. 3 is a similar view showing the flap adjusted in position to hold the return card with its end secured to the body of the envelope; Fig. 4 is a plan view of the front or address side of the envelope showing the end of the flap turned over the top edge of the envelope and secured thereto; Fig. 5 is a cross-sectional view of envelope and return 65 card arranged in the pocket on line 5—5 in Fig. 3; Fig. 6 is a plan view of a blank of a form adapted for a large sized envelope in which the flap for holding the return card is of different proportions; Fig. 7 is a 70 plan view of the reverse or back side of an envelope made from the blank shown in Fig. 6 with the return card flap turned outwardly in open position; Fig. 8 is a plan view of the same showing the flap in 75 secured position with a return card in the pocket; and Fig. 9 is a cross-sectional view on line 9—9 in Fig. 8.

My invention contemplates an envelope having a pocket formed on the back or sealed part of the envelope to receive and hold a return receipt card or other similar article. Preferably this is accomplished by so forming the blank from which the envelope is built up that after the envelope has 80 been formed a flap or strap of suitable width remains upon the back or sealed side of the envelope which may be secured in place, after the envelope has been filled and sealed, to form a pocket for the reception of the 85 return card. While my invention is designed especially for use in connection with registered mail, it is obvious that it is capable of many other uses.

Referring to the drawings, Figures 1 to 105 5 inclusive, I have shown one embodiment of my invention showing an envelope made up of a body-portion 10, with end flaps 11—11, side sealing flap 12 and an elongated flap 13 on the opposite side. In Figure 1 is shown 110 a blank from which the envelope may be made by turning over the two end flaps

11—11, one of the same being provided with adhesive 14. After the end flaps have been secured together by bending along the line 15—15 by means of adhesive 14, the 5 side flap 13 is then folded over on the line 17 the adhesive 18 being used to cement the flap to the two end flaps 11—11. These operations complete the envelope with the folding over of the flap 12 on the line 20 10 as shown in Fig. 2. The envelope is then ready for use. After the enclosure has been inserted and the flap 12 sealed upon the two end flaps 11—11, it is ready to be mailed.

15 The flap 13 provided with adhesive 21 on its free end, may be secured in position by folding the end 22 of the flap over the top side of the envelope into the position shown in Fig. 4. This may be done before 20 mailing or may be done by the postoffice employees when the letter is registered. By sealing the flap to the body of the envelope a pocket is formed between the back of the envelope and the flap 13 and into this pocket 25 may be inserted either a return receipt card 30 or any other card which is intended to travel with the envelope to its destination and either be returned or not.

In Figs. 6, 7, 8 and 9 I have shown a 30 slight modification of my invention, due to the fact that it is applied to an envelope of large size. In Figs. 1 to 5 inclusive the envelope shown is intended to represent an ordinary sized envelope, in which case the 35 return registration card approximating it in size, will fill up the pocket. Where a large sized envelope is used, as shown in Figs. 6 to 9, it is unnecessary to turn the pocket forming flap over the side of the envelope, but the end of it may be secured 40 by adhesive on the back of the envelope as shown in Fig. 8, thereby forming a pocket large enough to take the ordinary register card.

45 Although my invention is designed primarily for use in connection with registered mail, it is not to be limited thereto but is capable of various other uses where it is desired to have sealed envelopes carry either 50 return or other cards on the outside and open to inspection. The use of my invention in connection with registered mail has many distinct advantages. The return card is securely held within the pocket and 55 cannot become separated from the envelope during the handling to which mail is ordinarily subjected. Unquestionably, this fact may be productive of a large saving in clerk hire for the Government, and the eradication of an ever present source of 60 annoyance, inconvenience and loss to the public.

65 While I have shown my invention as applied to an envelope made from a single blank, it is to be understood that my inven-

tion is not limited thereto, since the envelope may be made in various ways and the pocket may be formed either from an integral part of the envelope or from a separate piece. Further, the relative proportions of the 70 pocket and envelope may be infinitely varied, since my invention may be embodied in many other constructions than those shown and described.

75 What I claim is:—

1. An envelope having a body-portion, two end flaps folded over said body-portion and secured together forming the back of said envelope, the lower edges of said side flaps being parallel to the lower edge 80 of said body-portion, a sealing flap on the upper side of said body-portion and a narrow side flap on the lower side of said body-portion folded over the lower edges of the end flaps and secured thereto, the central portion of said side flap being extended to form a band having its free end only provided with adhesive whereby after the envelope has been sealed the said band may be laid over the back of said envelope and its end secured to said envelope 85 at or near its upper edge in order to form a pocket adapted to hold a return registry card. 90

2. A blank for an envelope having a body-portion, two end flaps adapted to be folded over said body-portion and secured together to form the back of the envelope, a sealing flap on the upper side of said body-portion and a narrow side flap on the lower side of 95 said body-portion, said side flap having its central portion extended to form a band with its free end only coated with adhesive whereby after the envelope has been formed and sealed the said band may be laid over the back 100 of said envelope over said sealing flap and its end fastened to said envelope at or near the upper edge thereof in order to form a pocket upon the back of the envelope adapted 105 to receive and hold a card. 110

3. The combination with an envelope having a front portion for the address and a sealing flap on its back, of a band secured at one end to the lower side of the back of said envelope, and having its free end only provided with adhesive, whereby after the envelope has been sealed the said band may be laid over the back and sealing flap of said envelope and its end secured to said envelope at or near its upper edge, in order 120 to form a pocket adapted to hold a return registry card.

4. The combination with an envelope having a body-portion, two end flaps folded over said body-portion, and two side portions, one serving as a sealing flap and the other folded over with said end portions and secured together, forming the back of said envelope, of a band secured on the back 125 of said envelope adjacent the lower side 130

thereof and having its free end only provided with adhesive, whereby after the envelope has been sealed the said band may be laid over the back of said envelope and over said sealed flap and its end secured to said envelope at or near its upper edge, in order to form a pocket adapted to hold a return registry card.

5. The combination with an envelope having a front portion for the address and a sealing flap on its back, of a band secured at one end to one side of the back of said

envelope and having its free end only provided with adhesive whereby after the envelope has been sealed, the said band may be laid over the back of said envelope and over the said sealed sealing flap and its end secured to said envelope at or near its other edge in order to form a pocket adapted to hold tightly a return registry card. 15 20

In witness whereof, I hereunto set my hand this seventeenth day of April, 1919.

SIMON P. DILLON.
